UNITED STATES PATENT OFFICE.

GLADYS M. EDWARDS, OF DOUGLAS, ARIZONA.

THEFT-ALARM.

1,266,568.

Specification of Letters Patent. Patented May 21, 1918.

Application filed January 22, 1917. Serial No. 143,716.

To all whom it may concern:

Be it known that I, GLADYS M. EDWARDS, a citizen of the United States, residing at Douglas, in the county of Cochise, State of Arizona, have invented certain new and useful Improvements in Theft-Alarms; and I do hereby declare the following to be a full, clear, and exact description of the invention, such as will enable others skilled in the art 10 to which it appertains to make and use the same.

This invention relates to improvements in alarms.

One object of the present invention is to 15 provide a novel and efficient device for attachment to a pocket-book for the purpose of sounding an alarm, when an attempt is being made to open the pocket-book.

Another object is to provide a device of 20 this character which will sound the alarm when the pocket-book is opened and which will then remain idle and not sound the alarm when the pocket-book is again closed.

Another object is to provide a simple device 25 of this character which can be easily applied to the ordinary pocket-book, trunk or hand-bag without any great modifications to the same.

Other objects and advantages will be apparent from the following description when 30 taken in connection with the accompanying drawing.

In the drawing:

Figure 1 is a vertical sectional view 35 through a portion of a pocket-book, showing my invention applied thereto, the pocket-book being shown in open position.

Fig. 2 is a vertical sectional view taken on the line 2—2 of Fig. 1.

Fig. 3 is a top plan view of one side of 40 the closure of the pocket-book, partly broken away.

Fig. 4 is a top plan view of the clapper and latch showing the latter sliding from 45 the shoulder of the former.

Referring particularly to the accompanying drawing, 10 represents one side of the closure portion of the frame of a pocket-book, and 11 the other side thereof. The 50 side 10 is provided with the usual push button 12 having the projection 13 for engagement with the wall of the opening 14 in the other member 11. On the lower face of the

said projection there is formed a beveled lug 15. 55

Secured at one end to the member 11 and extending in parallel relation to the upper portion of the member, is a leaf spring 16, having on its free end a knob 17, and intermediate its ends a notched portion forming 60 a shoulder 18. The beveled lug 15 engages with the said shoulder when the pocket-book is in closed position, but when the same is being opened the said lug engages with and pulls the spring away from the member 11, 65 and finally snaps past the said shoulder so that the spring will be freed and permitted to swing back toward the member 11. Also secured on the member 11 is a bell 19 which is adapted to be struck by the knob of the 70 spring when the spring is freed from the lug 15. Thus any attempt to open the pocket-book will result in the ringing of the bell and the fact being immediately known by the owner in time to prevent the theft. 75

Attention is called to the fact that the lug 15 normally is out of engagement with the spring, and only engages the same when the button is depressed in the act of opening the pocket-book. Thus the bell will not be 80 rung when the pocket-book is being closed.

What is claimed is:

In a theft alarm the sides of a receptacle closure, one side of the closure being formed with a notch, the other side of the closure 85 having an apertured wall, a spring detent carried by the last-named side of the closure and projecting through said apertured wall, said detent having an arrow head one portion of which is arranged to engage a wall 90 of the said notch to hold the sides of the closure in closed position, a bell secured to the other side of the closure adjacent the notch, and a bell clapper including a flexible stem having a shoulder for engagement by 95 the other portion of the head of the detent when the receptacle is closed, said head being arranged to flex the clapper stem and slide from said shoulder when the sides of the closure are moved away from each other. 100

In testimony whereof, I affix my signature, in the presence of two witnesses.

GLADYS M. EDWARDS.

Witnesses:

GEORGE W. CASS,
FRANK E. BARB.
